UNITED STATES PATENT OFFICE.

EDWARD W. CRABTREE, OF HILLSBORO, NORTH CAROLINA, ASSIGNOR OF ONE-HALF
TO N. W. BROWN, OF ORANGE COUNTY, NORTH CAROLINA.

SAFETY STRAP FOR SHIPPING CRATES.

Application filed June 27, 1925. Serial No. 39,940.

To all whom it may concern:

Be it known that I, EDWARD W. CRABTREE, a citizen of the United States, residing at Hillsboro, in the county of Orange and State 5 of North Carolina, have invented certain new and useful Improvements in a Safety Strap for Shipping Crates, of which the following is a specification.

The present invention appertains generally 10 to devices for strengthening, bracing, and locking shipping crates, and more particularly to an improved strap which may be placed about the crate very quickly and will be prevented from becoming very easily removed in an unauthorized manner and yet may be quickly and easily removed when desired by an initiated person.

Another very important object of the invention is to provide a device of this nature 20 which is exceedingly simple in its construction, inexpensive to manufacture, efficient and reliable in use, strong and durable and otherwise well adapted to the purpose for which it is designed.

With the above and numerous other objects in view as will appear as the description proceeds, the invention resides in certain novel features of construction, and in the combination and arrangement of parts 30 as will be hereinafter more fully described and claimed.

In the drawing:—

Figure 1 is an elevation of a crate showing my improved strap applied thereto,

Figure 2 is a perspective view of the strap, and

Figure 3 is a detail section taken on the line 3—3 of Figure 2.

Referring to the drawing in detail, it will 40 be seen that A designates generally a crate of well known construction which is commonly used in shipping vegetables and the like. This crate has merely been disclosed so as to clearly demonstrate the utility of the invention, and it is obvious that my improved device as will hereinafter be described in detail is adaptable to numerous other designs of crates, boxes, and the like.

Having reference now particularly to my 50 improved device it will be seen that the numeral 1 designates the upper strap member, and the numeral 2 designates the lower strap member. The upper strap member 1 is of a substantial U-shaped formation including the main intermediate portion hav-

ing the two rectangularly disposed arms 3 and 4. The arm 3 is provided adjacent its terminal with an aperture 5 for receiving the looped end 6 of a link member 7. An aperture 8 is provided intermediate the ends 60 of the arm 4. The terminal of this arm 4 is bent to provide a sleeve 9 as is more clearly shown in Figure 3. The bottom strap member 2 includes the body intermediate portion having at its terminals the rectangularly disposed arms 10 and 11. The arm 10 is provided at its terminal with an aperture 12 for receiving the other terminal loop 13 of the link member 7. An aperture 14 is provided in the arm 11 and receives the loop 70 terminal 15 of another link member 16. The other end of the link member 16 is inserted through the sleeve terminal 9 and extended through the aperture 8 and then bent downwardly over upon itself as is clearly 75 indicated in the drawing.

When the device is initially applied to the crate A the link member 16 is disengaged from the arm. The link member 16 is straight, that is disengaged from the 80 arm 4. The strap member 2 is preferably applied transversely across the bottom, while the strap member 1 is applied transversely across the top, although the arrangement of these strap members may be reversed. The 85 link member 16 is then inserted through the sleeve terminal 9 and through the aperture 8 and bent downwardly over upon itself. It will thus be seen that the device braces the crate and positively prevents the lid 90 thereof from becoming accidentally open. The strap device also efficiently strengthens the crate and assists in preventing the same from breaking down as often happens owing to the rather rough usages to which said 95 crate is put. It is preferable to construct the strap members 1 and 2 of sheet metal, although any other suitable strong and durable material may be utilized.

It is thought that the construction, utility, 100 and advantages of my invention will now be clearly understood without a more detailed description thereof. The present embodiment has been disclosed in detail merely by way of example since in practice it attains the various features of advantage 105 enumerated as desirable in the statement of the invention and the above description. It will be apparent, however, that numerous changes in the details of construction, in the 110

sizes, and in the materials and in the combination and arrangement of parts may be resorted to without departing from the spirit or scope of the invention as hereinafter 5 claimed or sacrificing any of its advantages.

Having thus described my invention, what I claim as new and desire to secure by Letters Patent is:—

10 A device of the class described including a **U**-shaped strap member, link members pivotally engaged with the terminals of

said strap member, a second **U**-shaped strap member having one terminal pivotally engaged with one link member, and its other terminal formed in a sleeve and provided with an aperture so that the other link member may be inserted through the sleeve and through the aperture and then bent over upon itself. 15

In testimony whereof I affix my signature.

EDWARD W. CRABTREE.
